H. SMELSOR.

Churn.

No. 224,112.

Patented Feb. 3, 1880.

UNITED STATES PATENT OFFICE.

HENRY SMELSOR, OF ARCADIA, INDIANA.

CHURN.

SPECIFICATION forming part of Letters Patent No. 224,112, dated February 3, 1880.

Application filed November 24, 1879.

To all whom it may concern:

Be it known that I, HENRY SMELSOR, of Arcadia, in the county of Hamilton and State of Indiana, have invented certain new and useful Improvements in Churns; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to improvements in churns; and it consists in the construction and novel arrangement of the dasher, which causes the globules of the milk to break and separate while undergoing the operation of churning, whereby the production of butter is greatly facilitated.

20 The annexed drawings, to which reference is made, fully illustrate my invention, in which Figure 1 represents a vertical cross-sectional view of my improved churn. Fig. 2 represents a vertical longitudinal sectional view of the same. Fig. 3 represents a side view of the dasher detached from the churn, and Fig. 4 shows a detached cross-sectional view of the same.

The capital letter A designates a churn-body, 30 the lower portion or bottom of which is of cylindrical form, the same being constructed of any suitable material, and provided with legs a a, upon which the churn-body is supported, and it is also provided with a lid or cover, a', 35 on the top thereof, in order to close the opening through which the cream is poured into the churn. A groove, a², is also made on the inner face of one end of the churn-body, extending from near the center of the same vertically to the top of said churn-body A. In the end opposite said groove is made a perforation, below which, on the outer face of the churn-body, is placed a drip-spout, b'. A tube is also applied to one end of the churn-body, 45 the inner end of which is flaring and enters the interior of the churn. The purpose for which the above-mentioned perforation, groove, spout, and tube are intended will be hereinafter explained.

50 B indicates a revolving dasher placed within the churn-body A, and constructed with end pieces, b² b³, having radial arms b⁴, in which

are secured the dasher-blades b, that unite the end pieces, b² b³, to one another. Said dasher is also provided with curved bars c c, extending obliquely from one radial arm b to a similar arm on the opposite end of the dasher aforesaid. This construction of said curved bars causes them to cross one another at or near the center of the dasher B, and at the same time does not allow them to touch by such crossing. At one end of the dasher B is formed a perforation running crosswise through the center of the end piece b², the inner portion of which is provided with internal screw-threads, that receive the screw-threaded end of a rod, C. The opposite end thereof is formed into a crank having a handle, b⁵, by which the churn-dasher B is revolved.

Opposite the perforation above mentioned, 70 and in line therewith, is a lug or projection, a³, on the outer face of the end piece b³, and between the latter and the inner face of the churn A. Said lug or projection has its bearing in the bottom of a vertical groove, a², which 75 is open and extends to the top of the churn-body, as hereinbefore mentioned, and serves as a support for that end of the dasher B, while the perforation through the opposite end of the churn-body acts as a bearing and support for that end of the dasher aforesaid.

Having thus given a description of how I construct my improved churn-dasher, and the construction of the churn-body, I will now proceed and explain how the different parts 85 are operated in churning, removing the dasher for cleaning, drawing off the buttermilk, &c.

Operation: The cream is poured into the top of the churn A, as is usual, after which the lid or cover a', that fits snugly therein, is placed thereon, and the handle b⁵ on the crank. portion of the screw-threaded rod above spoken of is given a forward revolution, which has the effect of revolving the churn-dasher B within the churn-body A. At the same time the blades b agitate the cream and the curved bars c cause the milk to be thrown from the center of the churn-body, thereby compelling the blades b of the dasher B to act directly upon the cream that otherwise would remain with the buttermilk, as is the case with previously-constructed churning.

It will thus be seen by the foregoing description that a churn-dasher constructed as herein

described, and provided with the curved bars *c c*, is easily operated and causes the cream placed within the churn-body *A* to change to butter with very little labor, and at the same time the bars aforesaid allow no cream to mingle with the buttermilk after the operation of churning is completed; also, in order to remove the churn-dasher *B* from the interior of the churn-body *A* after churning, the operator may hold stationary the dasher *B* with one hand, and with the other hand reverse the movement of the crank to that of churning, thereby causing the rod *C* to unscrew and disengage with the dasher *B*. It is then (the rod) slightly or entirely withdrawn, which allows the dasher *B* to be lifted out for the purpose of giving ready access to the butter within the churn, and allowing the dasher and interior of the churn-body to be easily cleansed. Furthermore, in relieving the churn-body of the milk after the operation of churning, an ordinary plug is withdrawn from the mouth of a tube, *c'*, placed at the bottom of churn-body, and extending through the end 25 of the same and entering the interior thereof, with a flaring end opposite to that in which is inserted the plug above mentioned, and the milk passes out and into any suitable receptacle; also, the drip-spout *b'*, hereinbefore mentioned, being secured to the outside of the churn-body and directly below and partly encircling the rod *C*, catches all the milk that may find its way through the perforation in the end of the churn, and through which passes the rod aforesaid, and carries it off, and thus prevents it (the milk) from running on and besmearing the end of the churn-body *A*.

It will also be observed that in my construction of the dasher I dispense with a rod extending from end *b²* to the end *b³* of the dasher *B*, and apply the curved bars *c c*, thereby avoiding the possibility of the milk being drawn to the center of said dasher, as is the case with similarly-constructed churns, which prevents a portion of the cream from coming 45 directly in contact with the dasher-blades, thus causing a waste of cream; also, the dasher *B* and interior of the churn-body *A* can be thoroughly cleaned without separating one from the other simply by pouring water into the 50 churn and revolving the dasher by the handle several times, after which the plug aforesaid may be withdrawn and the water allowed to pass out from the interior of the churn.

Having described my invention, what I claim 55 as new, and desire to secure by Letters Patent, is—

The within-described dasher, consisting of the cross-heads *b² b³*, parallel dasher-blades *b b b*, curved bars or blades *c c*, attached to 60 the cross-heads *b² b³*, and crossing each other within the space of the parallel dasher-blades, all constructed, arranged, and operating in the manner herein set forth.

In testimony that I claim the foregoing I 65 have hereunto set my hand this 27th day of October, 1879.

HENRY SMELSOR.
